F. P. CROWE

ELECTRIC ALARM DEVICE FOR CLOCKS

Filed Feb. 6, 1924

INVENTOR,
Florence P. Crone,
By Howard S. Smith,
ATTORNEY.

UNITED STATES PATENT OFFICE.

FLORANCE P. CROWE, OF GREENFIELD, OHIO.

ELECTRIC-ALARM DEVICE FOR CLOCKS.

Application filed February 6, 1924. Serial No. 691,063.

To all whom it may concern:

Be it known that I, FLORANCE P. CROWE, a citizen of the United States, residing at Greenfield, in the county of Highland and

State of Ohio, have invented certain new and useful Improvements in Electric-Alarm Devices for Clocks, of which the following is a specification.

This invention relates to new and useful 10 improvements in electric alarm devices for clocks, and has particular reference to an electric alarm device which is easily attachable to the dial of any clock for operation by a hand of the latter.

15 It is the principal object of the invention to provide a simple and efficient device which may be easily attached to the dial plate of any clock for operation by its hour or minute hand to give an alarm at a predetermined time. The device is of few parts, they are economically and easily made, and when attached to the clock dial, they will form an alarm unit which is both attractive and efficient.

20 25 The invention contemplates the attachment of a wedge element to the hour hand of the clock, to close a circuit through an electric bell or other alarm device when that element engages the circuit closing means on the dial.

In the accompanying drawings, Figure 1 30 is a front view of the dial of a clock to which my alarm device is applied. Figure 2 is a diametrical, sectional view taken 35 through the dial and the setting slides of the alarm device. Figure 3 is a bottom plan view of the hour hand, showing the wedge contact element secured thereto. And Figure 4 is a rear view of the clock dial, showing the alarm bell and its electric connections with the tracks on the dial.

Referring to the accompanying drawings for a detailed description of my invention, the numeral 1 designates a clock dial around 40 which an hour hand 2 and a minute hand 3 travel in the usual manner. Secured to the front face of the dial 1 by screws 4, are two concentric tracks 5, 5 made of conducting material and having each a scarf-groove 6 in its outer side to receive a radial scarf-grooved slide 7 constructed of suitable conducting material. On the rear side of the

dial 1 the tracks 5, 5 are connected together by non-conducting pieces 8 through which the screws 4 pass. (See Figures 2 and 4.)

55 Secured to each track 5 for projection through a hole that may be easily formed in the dial 1, is a binding post 9 or other suitable wire-receiving element. Wires 10, 10 connected to these posts 9, 9, place the tracks 60 5, 5 in circuit with an electric bell 11, or any other suitable electric alarm. (See Figure 4.) This circuit is closed by the following means to give an alarm at a predetermined time.

65 The slides 7, 7 project a sufficient distance over the space between the tracks 5, 5 to permit a non-conducting bridge piece 12 to be secured, by screws 11, 11, to their bottom portions for travel around the circular path 70 between the tracks. (See Figures 1 and 2.) At each side of the bridge piece 12 there is formed on each slide 7 a radial housing 13 for a plunger 14 from which a pin 15 projects through a hole in the inner end of the 75 housing.

The plunger pins 15, 15 are in alinement with each other, but in their normal outward positions they do not meet so that they may leave sufficient space for the entrance between them of a wedge piece 16 attached to the bottom of the hour hand 2 of the clock. Mounted in each housing 13 is a compression spring 17 against which each plunger 14 will be pressed by the wedge 80 85 piece 16 when the latter is moved between the plunger pins 15, 15 by the hour hand; and after it has passed between these pins, the springs 17, 17 will return the plungers to their normal outward positions. The engagement of the wedge piece 16 with the plunger pins 15, 15 will close an electric circuit between the slides 7, the tracks 5 and the electric bell 11 through the means hereinbefore described, to cause the bell to ring 90 95 so long as the wedge piece is between said plunger pins.

The slides 7, 7 connected by the non-conducting strip 12, form together a setting arm or hand that is completed by a pointed projection 18 on the outer slide for passage over the time-division numerals 19 on the dial. Therefore, when it is desired to set the alarm for a certain time, the connected

slides 7, 7 may be easily moved around the dial 1 by the fingers to bring the pointed projection 18 over the numeral designating the hour or less division of time selected. 5 In Figure 5 the projection 18 on the outer slide 7 is shown to be directly over the numeral "3", so that when the hour hand 2 comes to a position over that numeral, or when it is five o'clock, the wedge piece 16 10 will move between the plunger pins 15, 15 to close the electric circuit through the bell 11 and thereby cause it to ring so long as the wedge piece is between the pins. The duration of time the bell is rung may be 15 varied by increasing or decreasing the length of the wedge piece, or it may be made to ring alternately by corrugating said wedge piece. The latter is also constructed so that the indicator may be freely moved 20 around the dial without injuring the hour hand 2.

The outer track 5 is formed in its periphery with notches 20 into which a plunger 21 mounted in a guide 22 on the interior of the outer slide 7, is adapted to be pressed by a spring 23 to set the indicator, and hold it firmly, in a selected position. The notches and safety plunger also prevent the indicator being moved in any direction other than the one in which it will pass the hour hand most easily. The safety plunger also prevents the indicator from dropping down on the left hand side of the dial.

35 To overcome lost motion and to insure that it will make contact on the exact minute for which the indicator is set, the hour hand 2 is preferably poised by an extension 24. (See Figures 1 and 3.)

40 The device is easily attached to the dial of any clock by first boring the necessary small holes to receive the screws 4, which are passed through said holes from the rear into the tracks 5, 5 which are concentrically positioned on the front face of said dial. Holes are also formed in the dial to receive the binding posts 9, 9 to which the wires 10, 10 45 may be easily connected. The slides 7, 7 are easily applied to the tracks, and the wedge piece 16 readily fastened to the hour hand, so that the entire operation of assembly and attachment of the device to the clock may be accomplished quickly, easily and without injury to the clock itself.

55 Having described my invention, I claim:

1. In a clock, the combination with a dial and a time-indicating hand movable around the latter, of a pair of concentric tracks attachable to said dial beneath said hand, a 60 slide free to travel around each track, non-conducting means connecting said slides for a movement together to a desired alarm position on the dial, an electric alarm device in electric circuit with said tracks, and a contact element on said time-indicating

hand adapted to be engagingly carried between said slides by the time-indicating hand, to close the electric circuit between the slides, the tracks and the alarm device for the purpose specified. 70

2. In a clock, the combination with a dial and a time-indicating hand movable around the latter, of a pair of concentric tracks attachable to said dial beneath said hand, a slide free to travel around each track, non-conducting means connecting said slides for a movement together to a desired alarm position on the dial, an electric alarm device in electric circuit with said tracks, plungers on said slides spring-pressed over the space 80 between the latter, and a wedge contact element on the time-indicating hand adapted to be engagingly carried between said plungers by the time-indicating hand, to close the electric circuit between the slides, the tracks 85 and the alarm device for the purpose specified.

3. In a clock, the combination with a dial and a time-indicating hand movable around the latter, of a pair of concentric tracks attachable to said dial beneath said hand, a slide free to travel around each track, a non-conducting element connecting said slides for a movement together to a desired position, a housing on each slide, a plunger 90 in each housing, a spring behind each plunger in its respective housing, a pin projecting outwardly from each plunger over the non-conducting element connecting the slides, an electric alarm device in electric 100 circuit with said tracks, and a wedge piece attachable to the time-indicating hand, adapted to be carried by the latter between the plunger pins, for engagement with the latter to close the electric circuit between the 105 slides, the tracks and the alarm device for the purpose specified.

4. In a clock, the combination with a dial and a time-indicating hand movable around the latter, of a pair of concentric tracks attachable to said dial, an indicator movable around said tracks, an alarm device in electric circuit with said tracks, a contact element on the time-indicating hand for contact with the indicator to close the electric 110 circuit through said alarm device, one of said tracks having notches in its periphery, and a safety plunger on the indicator adapted to engage in said notches to hold the indicator in a desired position. 115

5. In a clock the combination with a dial and a time-indicating hand movable around the latter, of a pair of concentric tracks adapted to be applied to the face of said dial, the latter being formed with holes behind said tracks, screws projecting through said holes into the tracks, radial non-conducting pieces held against the rear face of the dial by said screws, a slide adapted to travel 125 around each track, a non-conducting bridge 130

piece connected between the slides for movement through the path between the tracks, an electric alarm device in electric circuit with said tracks, and a contact element attached to said time-indicating hand adapted to be engagingly carried by the latter between said slides, to close the electric circuit

between the slides, the tracks and the alarm device for the purpose specified.

In testimony whereof I have hereunto set my hand this 31st day of January, 1924.

FLORANCE P. CROWE.

Witness:

HOWARD S. SMITH.
